Fig. 5

FIG. 1 is a front, top and left side perspective view of a combined bed and toy box showing my new design, the inside of the left side board being a mirror image of the right side board and the mattress support brackets being identical at the head and foot;

FIG. 2 is a right side elevational view;

FIG. 3 is a front elevational view, the rear of the foot structure being plain and unornamented;

FIG. 4 is a rear elevational view; and

FIG. 5 is a view similar to FIG. 1 of another embodiment of a combined bed and toy box showing my new design, wherein the locations of the head sliding doors and top panel have been transposed, with the left foot door in open position.

I claim:

The ornamental design for a combined bed and toy box, substantially as shown and described.
